YARN GUIDE

Harmon Howorth, Cumberland, Md., assignor to
Celanese Corporation of America, a corporation
of Delaware

Application August 21, 1935, Serial No. 37,133

3 Claims. (Cl. 242—157)

This invention relates to improvements in textile working devices, and more particularly to a roller guide to be used in place of guide eyes, etc. on yarn winding, twisting and coating machines.

An object of the invention is the construction of a guide, for yarn processing devices wherein the yarn travels from a supply package to a take-up package, that applies a rolling friction on the yarn. Another object of this invention is the production of a guide that has a longer life than guides heretofore used. Other objects of the invention will appear from the following detailed description and drawing.

In the drawing wherein like reference numerals refer to the same or similar elements:

Figure 1 is a front elevation, partly in section, of an assembled guide member constructed in accordance with this invention.

Figure 2 is an end view of the guide shown in Figure 1.

In the treatment of yarns wherein a lubricant, coating, size, plasticizer or the like is applied to yarn and in the twisting and rewinding of yarn, it is found advantageous to use roller guides for yarn control during the winding. The ordinary roller guide makes use of collars and flanges to hold the roller in place. Accordingly, much difficulty has been experienced from yarn-fly building up between the rolls and collars, which condition eventually effects a binding action on the roller guide, thus preventing the free turning of the same. Due to the difference in friction between the starting of the winding operation and the finishing of said operation when employing such yarn guide rollers as those now in use, there is produced a yarn which is not uniform. This lack of uniformity is due in part to a non-uniform application of the treating material, if any is applied, and to a non-uniform tension applied to the yarn. By the use of a roller guide member constructed in accordance with this invention, the yarn is wound, twisted, etc. under an even tension by virtue of the rolling friction, regardless of the denier, speed or uniformity of the yarn. Moreover, the construction of the roller guide is such that it cannot become bound by fly from the yarn.

In accordance with my invention, I construct a roller guide to be applied to rewinding, twisting and other devices wherein the yarn travels from one point to another, which roller guide is adapted to be used in place of the pig tail guides, porcelain eyes, porcelain or metal hooks and other forms of stationary guide members, as well as the unsatisfactory roller guides, now employed.

The roller guide of the instant invention consists of a roller adapted to rotate upon a stationary or rotatable axle and so constructed that it neither picks up nor accumulates fly thrown off from the yarn. The roller guide may be of any suitable material and of any suitable size to adapt it for contact with various reagents found in or upon the yarn and to the various sizes of yarn that are to be guided thereby. The body of the roller may be, for instance, wood, porcelain, brass, steel, etc. If a metallic body is employed it may be coated or plated with porcelain, rust and chemical resisting metallic coatings, shellac, etc.

Referring to the drawing, the guide may be formed of a roller 1 having a grooved track-way 2 adapted to retain a travelling yarn in a given position. The groove 2 may be of any suitable shape, for instance V shaped as shown in the drawing, or U shaped, and the pitch of the sides or the depth of the groove may be of any suitable degree or dimension. The outer ends 3 of the roller are preferably tapered from the outer margin, indicated by reference character A, of the groove 2 to the axle. The pitch of the tapered ends of the roller may be of any suitable degree, for example, from 30° to 80° from the axial line.

The roller 1 may be supported upon a shaft 4 in such a manner that it is free to rotate thereon. The shaft 4 may be formed or have milled thereon a shoulder 5 at one end thereof to accommodate a bearing surface 6 of the roller. The opposite end of the shaft 4 from the shoulder 5 is threaded as at 7 to accommodate a bearing sleeve 8. The bearing sleeve 8 may be a piece of tubing hardened at least at its inner end to act as a bearing, which tube has internal threads adapting it to be threaded on to the shaft 4, thereby forming another bearing 9 adapted to accommodate the bearing surface 11 of the roller. That part of the shaft 4 lying between the bearing tube 8 and the shoulder 5 may be formed of such a diameter with reference to the axial hole in the roller that the shaft and roller do not contact. If desired, and in certain cases it is preferable, that both ends of the shaft 4 be threaded in a manner similar to that shown in the drawing at 7 and both bearing surfaces may be formed from a tube or sleeve similar to tube 8. When tubes are employed as both bearing surfaces, they may be formed of pressed cellulosic materials to eliminate the use of oil which is necessary to prevent a binding action of metal against metal. The pressed cellulosic tubes may be formed of cellulose, with or without other wood products being present, and a binding agent that may also con-

55

tain a lubricant such as a very viscous grease, graphite, etc. The binding agent may be a natural or synthetic resin or a thermoplastic or thermosetting material.

5 The shaft 4 may be attached at one or both ends to suitable brackets mounted on a yarn winding, twisting or coating device in any suitable manner and location.

10 In operation, the yarn travelling from the supply package to a take-up package is passed in contact with the groove 2 of the roller 1 and is guided with a rolling friction. The roller with its enclosed bearing surface and tapered ends is so designed that the yarn-fly, as it falls upon 15 the roller sides, slips off the roller guide and will not bunch thereon to effect a binding action between the rotating guide and its bearing.

15 By employing this invention, the yarn is guided with a rolling friction, which rolling friction permits the production of a more uniform 20 yarn as well as yarn package. When the device of the present invention is employed as the guiding means of a coating device a more level application of the coating material is obtained 25 as there is less wiping action of the guide upon the coated yarn. Any fuzz or fly that comes from the yarn during twisting does not prevent the guide roller from turning which is the case when rollers of other shapes or when flanges are 30 used to hold the roller guide in place. This type of roller guide produces a more uniform friction on the yarn, resulting in the elimination of damaged yarn while at the same time the life of the 35 guide is much longer.

35 It is to be understood that the foregoing detailed description and drawing are given merely by way of illustration and that many variations

may be made therein without departing from the spirit of my invention.

Having described my invention, what I desire to secure by Letters Patent is:

1. As an attachment for a yarn processing device, a yarn guide for guiding the yarn with a rolling friction, comprising a shaft, a roller rotatably carried thereby, said roller having ends which taper towards the edges of said rollers down to the bore of said roller and, intermediate 10 said ends, a groove with which the yarn is adapted to contact in its travel, and means on the inside of said roller for positioning said roller axially on said shaft. 5

2. As an attachment for a yarn processing device, a yarn guide for guiding the yarn with a rolling friction, comprising a shaft, a roller rotatably carried thereby, said roller having ends which taper towards the edges of said roller down to the bore of said roller and a circumferential groove with which the yarn is adapted 15 to contact in its travel, and means on the inside of said roller for positioning said roller axially on said shaft. 20

3. As an attachment for a yarn processing device, a yarn guide for guiding the yarn with a rolling friction comprising a shaft, a roller rotatably carried thereby, said roller having ends which taper towards the edges of the roller down to the bore of said roller, a shoulder on said 25 shaft positioned inside said roller and adapted to act as one bearing member for said roller and a tube threaded on said shaft and having one end inside said roller so as to act as a second bearing member for said roller. 30 35
